BEDSPRING SUPPORT

Floyd E. Olson, Darlington, Wis.

Application May 21, 1948, Serial No. 28,321

8 Claims. (Cl. 5—238)

1

This invention relates to new and useful improvements in bed springs and the primary object of the present invention is to provide an attachment for the side sections of a bed spring that will adjustably and removably support the side rails of such bed springs on the side frame member of a bed.

Another important object of the present invention is to provide a bed spring support which is quickly and readily applied to the side sections of a bed spring during the manufacture thereof or which may be conveniently applied to the side sections of a bed spring after the same have been produced, and which embodies in its construction novel and improved adjusting and holding means that will prevent movement of the same when applied.

A further object of the present invention is to provide a bed spring supporting bracket or hanger that is extremely small and compact in structure and which will occupy very little space when in operation for supporting the side rails of a bed spring.

A still further aim of the present invention is to provide a bed spring support that is simple and practical in construction, strong and reliable in use, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a fragmentary perspective view showing one form of the improved support in application with sectional fragments of the bed-spring side-rail and the angle bar or side rail of the bedstead;

Figure 2 is a vertical sectional view taken substantially on the plane of section line 2—2 of Figure 1;

Figure 3 is a fragmentary perspective view showing a further form of the improved support applied to sectional fragments of the bed-spring side-rail and the angle-bar or side rail of the bedstead;

Figure 4 is a vertical sectional view taken substantially on the plane of section line 4—4 of Figure 3;

Figure 5 is a fragmentary perspective view showing a still further form of the present support applied to the bed-spring side-rail and the angle-bar of the bedstead;

2

Figure 6 is a vertical sectional view of the present support taken substantially on the plane of section line 6—6 of Figure 5; and

Figure 7 is a perspective view of the hanger element used in conjunction with the present invention.

Referring now to the drawings in detail, wherein for the purpose of illustration, there is disclosed a preferred embodiment of the present invention, the numeral 10 represents generally, the hanger element which is employed in all embodiments of the present bed support. This hanger element or bracket 10 includes a pair of substantially U-shaped members which are designated by the numerals 12 and 14.

The leg portions 16 of the member 12 are of a length less than the length of the leg portions 18 of the member 14 for a purpose which will later be more fully apparent.

Rigidly attached to or forming an integral part of the members 12 and 14 is a pair of inclined support elements or bars 20 that extend between the extremities of the leg portions 12 and 14. These bars 20 retain the members 12 and 14 spaced parallel to each other.

In practical use of the present invention as illustrated in Figures 1 and 2, an anchor plate 22 makes rigid contact with the supporting strip 24 mounted on the inner face of a bed side section 26. The members 12 and 14 embrace the anchor plate 22 and the legs 16 and 18 and bars 20 depend from the anchor plate to receive the side-rail or angle-bar 28 of a bed-spring. It is noted, that one leg of the angle-bar 28 bears against the lower face of the anchor plate 22 and the remaining leg of the angle-bar 28 bears against the leg portions 18 of the member 14.

A spacer or bearing block 30 is positioned upon the upper face of the anchor plate 22 and the web portions of the members 12 and 14 bear upon this block 30.

The block 30 is provided with a plurality of internally threaded openings 32 that receivably engage set-screws 34 having wing-type heads 36 which are adjusted to fix the block and hanger 10 relative to the anchor plate 22.

Reference is now directed to Figures 3 and 4, wherein there is disclosed a further method for securing the hanger 10 relative to the anchor strip 22. In this embodiment, the block 30 is not employed and the web portions of the members 12 and 14 are formed with internally threaded apertures or openings 38 that receivably engage set-screws 40 having wing-type heads 42. These set-screws 40 are adjusted to bear against the anchor plate 22 thus preventing

movement of the hanger 10 relative to the said anchor plate.

Reference is now directed to Figures 5 and 6, wherein there is disclosed a still further method for securing the hangers 10 to the anchor plate 22. In this embodiment, a pair of complementary wedge-strips 44 and 46 are driven between the anchor plate 22 and the web portions of the members 12 and 14.

With this latest construction, the hanger will be applied to the anchor plate 22 without the necessity of having to employ set-screws.

Obviously, in all embodiments of the present invention, a suitable number of anchor plates 22 and hangers 10 are employed for properly balancing and supporting the bed-spring.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. For use with angle iron bed rails, a bed spring support comprising an anchor plate, a first substantially U-shaped wire member embracing said anchor plate and including legs extending below said anchor plate, a further substantially U-shaped wire member embracing said anchor plate and having legs also extending below said anchor plate, the legs of said further member terminating below the legs of said first member, a pair of vertically inclined support elements joining corresponding legs of said members for supporting a bed rail, and means for removably securing said members to said anchor plate.

2. The combination of claim 1 wherein said means includes a plurality of set screws.

3. A bed spring support comprising an anchor plate, a first substantially U-shaped wire member embracing said anchor plate and including legs extending below said anchor plate, a further substantially U-shaped wire member embracing said anchor plate and having legs extending below said anchor plate, the legs of said further member terminating below the legs of said first member, a pair of support elements joining corresponding legs of said members for supporting a side rail, a spacer strip engaging said anchor plate and disposed between said anchor plate and the web portions of said members, and bearing elements adjustably carried by said strip.

4. A bed spring support comprising an anchor plate, a first substantially U-shaped member embracing said anchor plate and including legs extending below said anchor plate, a further substantially U-shaped member embracing said anchor plate and having legs extending below

said anchor plate, the legs of said further member terminating below the legs of said first member, support elements joining corresponding legs of said members for supporting a side rail, and a pair of complementary wedge members interposed between said anchor plate and the web portions of said members for holding the latter removably secured to the former.

5. A bed spring support comprising an anchor plate, a first substantially U-shaped member embracing said anchor plate and including legs extending below said anchor plate, a further substantially U-shaped member embracing said anchor plate and having legs extending below said anchor plate, the legs of said further member terminating below the legs of said first member, a pair of support elements joining corresponding legs of said members for supporting a side rail, and a set screw carried by the web portion of each of said members and engaging said anchor plate.

6. The combination of claim 1 wherein the legs of said first member are spaced from the legs of said further member a distance equal to the width of a bed rail to prevent rotation of a rail relative to said member, said support elements forming the sole support means for a rail.

7. In combination with an angle iron bed rail of a rail support, said rail support comprising an anchor plate, a first substantially U-shaped member embracing said anchor plate and having depending legs extending below the anchor plate and the rail, a second substantially U-shaped member embracing said anchor plate and having depending legs extending below the anchor plate and the rail, said angle iron rail including horizontal and vertical flanged portions, the horizontal flanged portion of said rail resting against the undersurface of said anchor plate, the vertical flanged portion of said rail resting against the legs of said second member and the outer edge of the horizontal flanged portion resting against the legs of said first member, and support elements joining the legs of said first member to the legs of the second member, the lower edge of said vertical flanged portion resting against said support elements.

8. The combination of claim 7 and means wedged between the anchor plate and the webs of said members to force the horizontal flanged portion of said rail against the undersurface of said anchor plate.

FLOYD E. OLSON.
